UNITED STATES PATENT OFFICE.

JAMES W. MALOY, OF SOMERVILLE, MASSACHUSETTS.

PAPER BAG.

SPECIFICATION forming part of Letters Patent No. 246,621, dated September 6, 1881.

Application filed January 12, 1881. (No model.)

To all whom it may concern:

Be it known that I, JAMES W. MALOY, of Somerville, in the county of Middlesex and State of Massachusetts, have invented certain 5 Improvements in Paper Bags, of which the following is a specification.

This invention relates to satchel-bottom paper-bags; and it consists in the improvements in a blank for paper bags and in a bag formed 10 from such blank, which I will now proceed to describe and claim, reference being made to the accompanying drawings, forming part of this specification, in which—

Figure 1 represents a plan view of a portion 15 of a web or strip of paper having blanks embodying my invention formed thereon. Figs. 2 and 3 represent enlarged plans of two adjacent blanks. Fig. 2^a represents a view of the bottom of a bag folded from the blank shown 20 in Fig. 2. Fig. 2^b represents a transverse section through said bag; Fig. 2^c, a similar section with the sides folded in. Figs. 3^a, 3^b, and 3^c represent corresponding views of the bag formed from the blank shown in Fig. 3.

25 In all the figures the same letters and figures of reference indicate similar parts.

In the drawings, A and B represent adjacent blanks for paper bags, formed from a continuous strip of paper by the straight cut c and the 30 irregular cut d. The cut c is simply a transverse cut, from side to side, of the strip of paper from which the blanks are made, and forms the top of the bag when the blank is folded, and it need not be further described. The irregular cut d produces V-shaped projections 35 e upon the blank A, alternating with depressions of similar shape, f. At the same time it produces upon the blank B, V-shaped depressions f', corresponding to the projections e, alternating with projections e', corresponding to the depressions f. The irregular cut d, besides producing the projections e e', with the corresponding depressions f f', on the blanks A and B, as just described, also makes slight longitudinal cuts n n' between the projections 40 e e' on each blank respectively, thus partially separating said projections at their bases and enabling the projections to overlap each other when the bags are folded, as hereinafter de-

scribed. The cuts c and d alternate with each other throughout the length of the strips of paper from which the blanks are made, thus producing a continuous series of blanks.

The blanks, being thus made, are folded by the following operation, reference being made 55 to the blank A shown in Fig. 2. The sides of the bag 1, 2, 3, and 4 are folded on the dotted lines k, l, m, and s. The edge i of the blank being brought to meet the line s, and the part 5 of the blank made to overlap the side 1 of 60 the blank, the bag may be gummed together. By this operation the projections e e e are brought into such relations to each other that they may be folded over toward each other like the flaps of an ordinary letter-envelope, as 65 shown in Fig. 2^a, their edges overlapping, and thus, when gummed together, forming the bottom of the bag. By a similar operation the blank B may be folded, the bottom of the completed bag formed therefrom being shown in 70 Fig. 3^a.

By forming the bottom of the bags in the manner above described it is obvious that all waste of material is avoided, the overlapping being simply sufficient to secure the requisite 75 strength when the bag is gummed together. By making the portions 2 and 4 of the blank A wider than the portions 1 and 3, a bag of oblong shape may be produced; and by increasing the number of projections e e' formed on 80 the blanks, and correspondingly increasing the number of folds, bags of six, eight, or any desired number of sides may be readily made.

I am aware that it is not new to form blanks 85 for paper bags by alternately severing a strip by straight and irregular cuts, forming respectively the tops and bottoms of the blanks; but I am not aware that a blank has been formed with partially-separated V-shaped projection at its lower end adapted to overlap and 90 form envelope folds or flaps.

Having thus described my invention, what I claim is—

1. The improved blank for paper bags herein described, having one end made by a transverse cut to form the top of a bag and the other end made by an irregular cut, producing 95 partially-separated V-shaped projections on the

blank, adapted to overlap each other when folded to form the bottom of the bag, as set forth.

2. The improved satchel-bottom paper bag, having its bottom made by overlapping envelope-folds, formed by partially-separated V-shaped projections upon the blank from which the bag is formed, as set forth.

In testimony whereof I have signed my name to this specification in the presence of two subscribing witnesses.

JAMES W. MALOY
